UNITED STATES PATENT OFFICE.

DAVID G. GRAY, OF VANCOUVER, BRITISH COLUMBIA, CANADA.

COMBINATION SQUARE AND LEVEL.

Application filed October 6, 1926. Serial No. 139,871.

This invention relates to a combination square and level wherein an integrally-square steel blade is pivotally mounted within a stock in which provision is made for 5 clamping and locking the blade in various angular or longitudinal positions so that it may be used either as a framing-square, a try-square, or as a bevel stock.

Imbedded within the stock of the square 10 are two levelling tubes, one having its axis parallel with the edge of the stock and the other at right angles thereto, so that they may be used for levelling or in connection with the square for plumbing determina- 15 tions.

The invention is fully described in the following specification, reference being made to the drawings which form part of this application, in which:

20 Fig. 1 is a face view of the square and stock in an elongated form with the stock opened out at the hinge.

Fig. 2 is also a face view of the tool for use as a try-square, the dotted lines showing its use with the blade as set for a bevel stock.

Fig. 3 is a face view of another form of try-square with the alternative position for the stock as shown in dotted lines whereby 30 an angle of forty-five degrees is immediately obtainable.

Fig. 4 is an alternative combination to that of Fig. 3 in which the short end of the integral square is pivotable, giving various 35 angular adjustments in relation to the edge of the stock as a base line.

Fig. 5 shows an edge view of the stock in its folded position either for portability or for use as a level.

40 Fig. 6 is a similar view but with the stock unfolded.

Fig. 7 being a front view of the latter.

In these drawings 8 represents the longer of a steel-bladed square having its shorter 45 arm 9 preferably two-thirds the length of the longer arm 8. The edges of these blades 8 and 9 are graduated outwards from the right angle in each case and the longer blade is apertured as shown by the longitudinal 50 slots 10 and 11 and the pivoting holes 12 and 13. The stock is composed of two members 14 and 15 hinged together at 16 and being of sufficient length to receive between them the shorter blade 9 of the removable 55 square.

The pin 17 (Fig. 5) is secured in one of

the stock members 14 and is threaded to receive a wing nut 18 by which the two members of the stock are clamped together on the blade 8 or 9.

The pivot hole 12 is so positioned that when the folded stock 14, 15 is swung over so that its extremity engages the edge of the shorter arm 9 and angle of forty-five is made by the corresponding edge of the stock. This pivot hole 12 forms no part of the slots 10 and 11 because it is important that this mitering angle should be immediately available in practical working without observation.

In one edge of the stock member 15 a level tube 19 is secured with its axis parallel with the edge of the stock and in the same stock member another level tube 20 is secured, the axis of which is at right angles 75 to the edge of the stock.

The semicircular extremity of the slot 10 is so positioned in relation to the pivot pin 17 that the outer edge of the short member 9 exactly coincides with the edge of the stock 80 when the stock members are positioned to embrace said member 9. The blade 8 is slotted at 10 and 11 in order that it may be adjusted to various lengths and secured at such positions by the pivot pin 17 and the 85 wing nut 18 to facilitate repetition measurements.

The face of the short blade 9 is also marked with suitable angular divisions as shown at 22 and 23. A locking device for 90 the short end of the square is provided by the catch 24 which engages a slot 25, thus holding the square blade 8 in a rigid right angular position in relation to the stock.

So constructed this combined tool affords 95 a large variety of convenient applications in the work of a carpenter or builder. All the special adaptations of the tool are designed to facilitate, simplify, and accelerate practical operation.

Apart from the stock, the square 8, 9 may be used as an ordinary framing square. With the blade mounted in the stock and secured by the pin 17 in the right angular position it may be used as a try-square, or 105 with the level 19 may be used for testing a vertical post, or the blade 8 may be turned to alignment with the stock 14, 15 as shown in Fig. 1 and will thus afford a long base for the use of the level 19.

The square 8, 9 may be readily released from its right angular position by slacken-

ing the wing nut 18 when it can be slid along the slot to any desired position and set to any desired angle as a bevel stock, and should this position be undesirable or inconvenient it can be released from the position shown in Fig. 4 and reversed.

Having now fully described my invention what I desire to be protected in by Letters Patent, is:—

- 10 1. The combination with a flat bladed square, of two stock members, a hinge uniting the two said members to one another at one end, means at the other end of said members for pivotally mounting the square between them and for securing the blade of the square at any desired angular position in relation to the stock.
- 15 2. The combination with a flat bladed square having one of its members apertured with a longitudinal slot, of two stock members, a hinge uniting the two said members

to one another at one end, and means passing through said slot and the free ends of said stock members for pivotally mounting the square between them and for securing the blade of the square at any desired angular position in relation to the stock. 25

3. The combination with a flat bladed longitudinally slotted square having a pin aperture in one of the two blades, of two stock members, a hinge uniting the two said members together at one end and adapted to receive and hold the blade of the square between them, a pin with a threaded end and nut secured on the free end of one of the stock members and passing through an aperture in the other on which pin the said square may be mounted, and may be secured by the nut in any desired position of angular adjustment in relation to the stock. 30 35 40

In testimony whereof I affix my signature.

DAVID G. GRAY.
